WASTE AND OVERFLOW FITTING

Vernon P. Steele, Fairfield, Conn., assignor to
Kenco Products Corporation, New York, N. Y.

Application December 16, 1948, Serial No. 65,633

3 Claims. (Cl. 4—199)

1

This invention relates to a waste and overflow fitting.

One of the objects of this invention is to provide a waste and overflow fitting which is simple, practical and thoroughly durable. Another object is to provide a fitting of the above type which has a minimum of individual parts, thus greatly facilitating the assembly thereof. Another object is to provide a fitting of the above character which may be quickly and easily operated by the user. Another object is to provide a fitting of the above character which is well adapted to withstand the wear and tear of hard use. Another object is to provide a fitting of the above character whose manufacture will be economical both from the standpoint of labor and materials used. Still another object is to provide a fitting of the above character which will not clog or be damaged by foreign material passing through the drain valve. Other objects will be in part obvious and in part pointed out hereinafter.

The invention accordingly consists in the features of construction, combinations of elements, and arrangements of parts, all as will be illustratively described herein, and the scope of the application which will be indicated in the following claims.

In the accompanying drawing, in which is shown one of the various possible embodiments of this invention,

Figure 1 is a vertical section taken through my waste and overflow fitting mounted on a sink, certain parts being shown in elevation and other parts being broken away for purposes of illustration;

Figure 2 is a horizontal section on an enlarged scale taken on the line 2—2 of Figure 1;

Figure 3 is a vertical section on an enlarged scale taken on the line 3—3 of Figure 1; and

Figure 4 is an elevation on an enlarged scale of a portion of the waste and overflow fitting shown on the line 4—4 of Figure 1.

Similar reference characters refer to similar parts throughout the several views of the drawing.

Referring now to Figure 1, the waste and overflow fitting, generally indicated at 10, is designed for use with any sink, such as sink 11, but is preferably used in the type of sink used at soda fountains and other places where considerable waste matter may pass down the drain. In fittings of this type, considerable difficulty has heretofore been experienced because the valves very often become clogged with waste material, such

2

as strings from dish rags and mops. Also, solid foreign bodies, such as pieces of glass and grit, very often damage or adversely affect the efficient operation of the valve structure. It is accordingly another object of this invention to provide a waste and overflow fitting, the operation of which will not be affected by either clogging materials, such as those mentioned above, or gritty solid particles.

10 In general, the fitting includes a cup, generally indicated at 12, which is connected by a pipe 13 to one of the openings in a T joint, generally indicated at 14. A slotted resilient sleeve, generally indicated at 15, is slidably mounted within 15 T joint 14 and acts as a slide valve to open or close the port through which waste enters the T joint from pipe 13. Sleeve 15 is moved up and down within joint 14 by means of a rod 16 which is connected thereto and which extends upwardly through pipe 17 and elbow 18. The upper end of rod 16 extends outwardly into the upper portion of the sink through the overflow openings formed in the surface of a flange nut, generally indicated at 19.

25 Specifically, the sink 11 has four walls, two of which are shown at 11a and 11b and a bottom 11c. A circular opening 20 is formed in the bottom 11c of sink 11, and the periphery of opening 20 is flanged downwardly. Cup 12 is positioned

30 beneath opening 20 and is mounted on the sink by means of a flanged nut 21. The threads on the outer surface of the lower portion of flange nut 21 thread into complementary threads in the inner surface of the upper portion of cup 12

35 to securely fasten the cup to the bottom of the sink. A gasket 22 is provided between the upper edge of cup 12, which flanges outwardly, and bottom 11c of sink 11 to prevent leakage at this point. A detachable basket 43 is mounted on

40 flange nut 21 to strain waste matter passing through cup 12. Pipe 13, which has an elbow 13a therein and an annular flange 13b formed on its upper end, is connected to the lower portion 12a of cup 12 by a lock nut 23. A gasket 24

45 is positioned between the upper surface of flange 13b and the lower surface of cup 12 to prevent leakage at this point. The left-hand end of pipe 13 extends into the foot portion 14a of T joint 14, and it is connected thereto by means of a lock

50 nut 25 and a gasket 26.

The inner surface of the T portion 14b of T joint 14 is machined to provide a smooth surface on which sleeve 15 slides. Sleeve 15, which preferably has an external diameter the same as the 55 internal diameter of the head portion 14b of

the T portion 14b, is machined to provide a smooth surface on which sleeve 15 slides. Sleeve 15, which preferably has an external diameter the same as the 55 internal diameter of the head portion 14b of

T joint 14, is preferably made from resilient brass tubing, and has a slot 27 (Figures 1 and 3) extending longitudinally thereof on the side of said sleeve positioned away from the waste port 28 when in operation. After sleeve 15 is slotted, it is preferably spread, so that when in operation within T joint 14, it is self-biasing when compressed, and exerts resilient pressure against the side walls of T portion 14b which holds it in contact with the inner surface of the T joint surrounding port opening 28. Slot 27 is directly opposite the vertical axis of port 28 so that sleeve 15 is evenly pressed into engagement with the side of portion 14b in which port 28 is positioned. As will be seen from the showings in Figs. 1 and 3 of the drawings, the ends of valve member 15 are cut on the bias, that is at an angle, so that the slotted side of the member is appreciably longer than the opposite side thereof which serves to close inlet port 28 of the T joint 14. Because of the slanting ends, member 15 will more readily cut grease and other matter which may line or clog any part of the head section 14b of T joint 14 and insure its rapid removal through drain pipe 43.

The lower end of rod 16 is T-shaped and has a T portion 16a, the ends of which are journaled in and secured to sleeve 15. The sides of sleeve 15 are pressed inwardly to form aligned, inverted bosses or dished portions 29 and 30 (Figures 2 and 3) through which aligned holes 31 and 32 are drilled. The T portion 16a of rod 16 is of sufficient length so that when its ends are seated in position in holes 31 and 32, they slightly clear the side walls of the T portion 14b of T joint 14 (Figures 2 and 3). By providing inverted bosses or dished portions in sleeve 15, it is strengthened, and, at the same time, a simple, positive and inexpensive connection is formed between rod 16 and sleeve 15.

A pipe 17 having a flanged lower end 17a is connected to the upper end of T joint portion 14b by means of a lock nut 33. A gasket 34 is positioned between flange 17a and the upper end of T head portion 14b to prevent leakage at this point. The upper end of pipe 17 extends into elbow 18 and is secured thereto by any suitable manner, such as by brazing 35. The right-hand opening in elbow 18, as viewed in Figure 1, is positioned in alignment with a circular overflow opening 36 formed in side wall 11a of sink 11. A flange nut 19 is threaded into the inside of elbow 18 and secures elbow 18 to sink 11. Gasket 38, which is positioned between sink 11 and elbow 18, prevents leakage around elbow 18.

The flange nut 19 (Figures 1 and 4) has a solid center portion 19a in which are formed a plurality of overflow openings 40 and 41. Opening 41 is in the form of a cross, one of the slots of which is vertically positioned. Rod 16 extends outwardly through the vertically positioned slot in nut 19 and has a knob 42 secured to its upper end.

In operation, sleeve 15 is moved upwardly and downwardly by means of knob 42, and friction between the outer surface of sleeve 15 and the inner surface of the T portion 14b of T joint 14 will positively hold sleeve 15 in any adjusted position. Thus, it will be seen that sleeve 15 may be adjusted to any desired position in member 14 so that rate of drainage from sink 11 may be at any desired rate. Furthermore, it will be seen that the waste matter passing down pipe 13 and through T joint 14 has a free passage so that it

cannot clog the valve. Any waste matter collecting in port 28 will be sheared by the angular lower edge of valve 15, and any solid foreign gritty matter, such as glass, has a clear path so that it can pass downwardly into waste pipe 43. The particular type of connection between the sleeve and rod is of major importance, because, as pointed out hereinabove, the inverted bosses in the sleeve materially strengthen it at the sides and also provide a simple and economical manner of connecting the rod to the sleeve.

It will thus be seen that a thoroughly efficient and practical waste and overflow fitting has been described in which the several objects mentioned hereinabove, as well as many others, have been successfully accomplished.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

I claim:

25. 1. A valve of the character described comprising a T-shaped hollow casing, a sink drainage connection to the stem of the T, the said stem being horizontally disposed; an overflow connection to the vertically disposed upper leg of the head of the T; a waste pipe connection to the bottom leg of the T; a vertically split, self-expanding hollow valve member slidably mounted in said casing and movable to open and close said sink drainage connection, said valve member having a longitudinal trapezoidal cross-section 30 in the axial plane of the vertical split; a rigid cross-arm journaled in said hollow valve member at right angles to the plane of said vertical split and an operating stem fixedly connected to the cross-arm.

2. The combination of a cylindrical valve chamber having a port in the wall thereof; a spring metal expandable hollow valve slidably mounted in said chamber for controlling said port, said valve being vertically slotted in an axial direction opposite said port to permit expansion thereof into sealing contact with the wall of the chamber, aligned bosses in the valve at right angles to the plane of said vertical slot, said bosses having aligned apertures; a rigid cross-arm journaled in said bosses; and a rigid valve-actuating member integral with said cross-arm.

3. The combination of a cylindrical valve chamber having a port in the wall thereof; an open ended tubular valve member slidably mounted in said chamber for controlling said port, the wall of said tubular valve member having integral spring biased engagement with the wall of the chamber, aligned bosses in the valve at right angles to the axis of the valve, said bosses having aligned apertures; a rigid cross-arm journaled in the bosses; and a rigid valve-actuating member fixedly connected to the cross-arm.

VERNON P. STEELE.
